NELS KROHN, OF CHICAGO, ILLINOIS, ASSIGNOR TO THE ADAMS & WESTLAKE COMPANY, OF CHICAGO, ILLINOIS, A CORPORATION OF ILLINOIS.

BRAKE-OPERATING MECHANISM.

1,178,585.

Specification of Letters Patent. Patented Apr. 11, 1916.

Application filed July 19, 1915. Serial No. 40,723.

To all whom it may concern:

Be it known that I, NELS KROHN, a citizen of the United States, and resident of Chicago, county of Cook, and State of Illinois, have invented certain new and useful Improvements in Brake-Operating Mechanism, of which the following is a specification, and which are illustrated in the accompanying drawings, forming a part thereof.

10 The invention relates to mechanism for operating brakes of railway cars, its objects being to secure simplicity of construction and ease of operation.

The invention consists of a structure such as is hereinafter described and as illustrated in the accompanying drawings, in which—

Figure 1 is a sectional view on the line 1—1 of Fig. 2; Fig. 2 is a detail elevation of the device, some parts being broken away; 20 Fig. 3 is a detail section on the line 3—3 of Fig. 1; and Fig. 4 is an inverted view of a portion of the mechanism housing.

The brake staff 10 is of ordinary form, its upper end being journaled in a bracket 11 adapted for attachment to the wall of a car. An operating ratchet 12 is fixed upon the staff above the journal, and a holding ratchet 13 is fixed thereon below the bracket. A hand-operated pawl 14, pivoted to the bracket 11, coöperates with the holding ratchet 13. A head, preferably in the form of a casing 15, is swiveled upon the upper end of the staff adjacent the ratchet 12, which, as shown, it incloses. Upon or within 30 this casing a pawl 17, for coöperating with the ratchet 13, is oscillatably mounted, preferably being provided with a pivot pin 16. A handle 18 is pivotally attached to the pawl, as shown at 19, and projects through 40 a suitable aperture 20 in the casing 15, affording means for throwing the pawl into and out of engagement with the ratchet.

The casing aperture is of greater width than the thickness of the handle, thereby permitting the necessary movement of the handle with reference to the casing to oscillate the pawl upon its pivot 16, for the purpose of controlling its engagement with the teeth of the ratchet. The initial movement of the 45 handle in the direction for winding up the brake throws the nose of the pawl into en-

gagement with the ratchet, and the initial movement of the handle in the opposite direction disengages the pawl therefrom. The casing aperture extends into the lower wall 55 21 of the casing, the inner end of this extension being contracted, one of its edges 22 being inclined to form a cam surface for engagement by the handle as it is lowered, thereby releasing the pawl from the ratchet. 60 Preferably the cam face 22 is so formed that the lowering of the handle to a position approximately forty-five degrees effects the disengagement of the pawl.

For a quick release of the brake the operating handle is dropped or allowed to remain in its lowered position, and the pawl 14 is disengaged from the ratchet 13. A gradual or partial release of the brake is effected by holding the operating handle in its upper position, releasing the pawl 14, swinging the operating handle backwardly, and again engaging the ratchet 13. Should further release be desired the operating handle may be dropped sufficiently to disengage 75 the pawl 17 from the ratchet 12 and swung forward while still in its lowered position. Upon again raising the handle the holding pawl may be disengaged and the brake further released by swinging the operating 80 handle backwardly, as before.

Preferably, as shown in Fig. 3, the two ratchets are formed as an integral casting, the intervening metal forming a hub which fits and turns within the box 23 forming the staff bearing. The attachment of the ratchet block to the staff may be by means of a pin 24 set through this hub. The location of the holding ratchet near the upper end of the staff is, however, not essential—the setting 85 mechanism being capable of use in connection with the ordinary foot-controlled holding device.

While the device described constitutes an operative and desirable form of construction, the invention is of broader scope than the particular embodiment shown, as, for example, the manner of oscillatably mounting the pawl within the casing, and

I claim:

1. In car brake mechanism, in combination, a staff, a ratchet on the staff, a head

100

- oscillatable about the axis of the staff, a handle mounted on the head and having lateral movement relatively thereto and being provided with a pawl for coöperating 5 with the ratchet.
2. In car brake mechanism, in combination, a rotatable staff, a ratchet fixed on the staff, a head oscillatable on the axis of the staff, a pawl oscillatably mounted on the 10 head and coöperating with the ratchet, a handle attached to the pawl and having lateral movement with reference to the head.
3. In car brake mechanism, in combination, a rotatable staff, a ratchet fixed on the staff, a head oscillatable on the axis of the staff, a pawl pivotally mounted on the head and coöperating with the ratchet, a handle 15 attached to the pawl and having lateral movement with reference to the head.
4. In car brake mechanism, in combination, a rotatable staff, a ratchet fixed on the staff, a head oscillatable on the axis of the staff, a pawl pivotally mounted on the head 20 and coöperating with the ratchet, a handle pivotally attached to the pawl and having lateral movement with reference to the head.
5. In car brake mechanism, in combination, a rotatable staff, a ratchet fixed on the staff, a head oscillatable on the axis of the staff, a pawl pivotally mounted on the head 25 and coöperating with the ratchet, a handle pivotally attached to the pawl and having lateral movement with reference to the head, 30 and a cam on the head for deflecting the handle laterally as it swings toward the staff.
6. In car brake mechanism, in combination, a rotatable staff, a ratchet fixed on the staff, a head oscillatable on the axis of the staff, a pawl pivotally mounted on the head 35 and coöperating with the ratchet, a handle pivotally attached to the pawl and having lateral movement with reference to the head, 40 and a cam on the head for deflecting the handle laterally as it swings downwardly on its pivot.
7. In car brake mechanism, in combination, a staff, a ratchet fixed on the staff, a pawl carrier oscillatable about the axis of the staff, a pawl carried by the carrier for coöperating with the ratchet, a handle pivotally mounted to swing toward and away 45 from the staff and to oscillate transversely thereto, such handle being adapted to engage the pawl with the ratchet when moved in one direction about the axis of the staff and to withdraw the pawl from the ratchet when swung toward the staff.
8. In car brake mechanism, in combination, a staff, a ratchet fixed thereon, a pawl coöperating with the ratchet, an oscillatable support for the pawl, an oscillatable drop handle arranged to move the pawl into en- 50 gaging relation with the ratchet when moved in one direction of its oscillation and to withdraw the pawl from the ratchet when dropped.
9. In car brake mechanism, in combination, a staff, a ratchet on the staff, a casing 55 mounted to oscillate about the staff, a pawl pivotally mounted within the casing and coöperating with the ratchet, a hand lever pivotally supported within the casing for vertical movement and projecting through and having lateral movement in an opening in the casing, such opening having one of its side walls inclined toward the median line of the hand lever, such lever being adapted by its lateral movement in one direction to 60 force the pawl into engagement with the ratchet.
- 10. In car brake mechanism, in combination, a rotatable staff, a ratchet fixed on the staff, a casing oscillatable on the axis of the staff, a pawl oscillatably mounted within the casing and coöperating with the ratchet, a handle attached to the pawl and having lateral movement with reference to the casing. 65
11. In car brake mechanism, in combination, a rotatable staff, a ratchet fixed on the staff, a casing oscillatable on the axis of the staff, a pawl oscillatably mounted within the casing and coöperating with the ratchet, a handle pivotally attached to the pawl and having lateral movement with reference to the casing. 70
12. In car brake mechanism, in combination, a rotatable staff, a ratchet fixed on the staff, a casing oscillatable on the axis of the staff, a pawl oscillatably mounted within the casing and coöperating with the ratchet, a handle pivotally attached to the pawl and having lateral movement with reference to the casing, and a cam on the casing for deflecting the handle laterally as it swings on its pivot. 75
13. In car brake mechanism, in combination, a rotatable staff, a ratchet fixed on the staff, a casing oscillatable on the axis of the staff, a pawl oscillatably mounted within the casing and coöperating with the ratchet, a handle pivotally attached to the pawl and having lateral movement with reference to the casing, and a cam on the casing for deflecting the handle laterally as it swings downwardly on its pivot. 80
14. In car brake mechanism, in combination, a staff, a ratchet on the staff, a casing 85 mounted to oscillate about the staff, a pawl oscillatable within the casing and coöperating with the ratchet, a hand lever pivotally supported within the casing for vertical movement and projecting through and having lateral movement in an opening in the casing, such opening having one of its side walls inclined toward the median line of the hand lever, such lever being adapted by its lateral movement in one direction to 90 force the pawl into engagement with the ratchet.

hand lever, such lever being adapted by its lateral movement in one direction to force the pawl into engagement with the ratchet.

15. In car brake mechanism, in combination, a staff, a ratchet fixed thereon, an element oscillatable about the staff axis, a pawl pivoted on such element for coöperating

with the ratchet, and an oscillatable drop handle arranged to move the pawl radially toward the ratchet when moved in one direction of its oscillation and to withdraw the pawl from the ratchet when dropped. 10

NELS KROHN.
